UNITED STATES PATENT OFFICE.

WILLIAM T. BLACKWELL, OF WESTFIELD, NEW JERSEY.

DESIGN FOR A REFLECTOR FOR USE IN LIGHTING FIXTURES.

Application filed April 4, 1925. Serial No. 13,019. Term of patent 7 years.

To all whom it may concern:

Be it known that I, WILLIAM T. BLACKWELL, a citizen of the United States, residing at Westfield, county of Union, and State of New Jersey, have invented a new, original, and ornamental Design for a Reflector for use in Lighting Fixtures, of which the following is a specification, reference being had to the accompanying drawing, forming part thereof, in which—

Figure 1 is an elevation of a reflector for use in lighting fixtures showing my new design, and

Fig. 2 is a bottom view of the same.

I claim:

The ornamental design for a reflector for use in lighting fixtures, as shown.

WILLIAM T. BLACKWELL.
